DESIGN.

—o—

J. C. GILL.

PAPER WEIGHT, MATCH SAFE, &c.

No. 17,148.

Patented Mar. 1, 1887.

UNITED STATES PATENT OFFICE.

JAMES C. GILL, OF COVINGTON, KENTUCKY, ASSIGNOR TO THE HEMINGRAY
GLASS CO., OF SAME PLACE.

DESIGN FOR A PAPER-WEIGHT, MATCH-SAFE, &c.

SPECIFICATION forming part of Design No. 17,148, dated March 1, 1887.

Application filed January 22, 1887. Serial No. 225,209. Term of patent 3½ years.

To all whom it may concern:

Be it known that I, JAMES C. GILL, a citizen of the United States, residing at Covington, in the county of Kenton and State of Kentucky, have invented and produced a new and original Design for Paper-Weights or Match-Boxes or Inkstands, of which the following is a specification, reference being had to the accompanying drawing, forming part thereof.

10 The drawing is a side elevation of my newly-designed inkstand or match-box.

The leading feature of my design consists in a representation of an anvil set on a stump—that is, a block of wood representing a section 15 of the trunk of a tree in its natural state, with the bark on—the object being to make the article look as nearly as possible like a blacksmith's anvil in position for work, the body of the anvil having a hollowed-out receptacle

or interior with rectangular opening at the top, 20 as shown. The broad face of the anvil may receive any desired inscription.

I am aware that I am not the first to use an anvil as an element of a design, and do not claim it broadly; but

25 I claim—

The design for a match-safe or inkstand herein described, consisting of a representation of a blacksmith's anvil set upon a stump or block of wood in its natural state—that is, 30 with the bark on—the body of the anvil having the hollowed out receptacle or interior with the rectangular opening at the top, as shown and described.

JAMES C. GILL.
